TWIN SEAT LAWN SWING

Charles J. Kliss, Garfield, N. J.

Application February 15, 1946, Serial No. 647,808

2 Claims. (Cl. 155—64)

1

This invention relates to an improved lawn swing, and one of its objects is to provide a swing construction which will be safe, light and portable, and extremely strong and dependable, and capable of supporting two persons for swinging.

Another object of the invention is to provide a lawn swing with inclined upright supports, and a bar holding the upper ends of the uprights in spaced relation to each other by means of plates welded diagonally to the ends of the bar and bolted to the upper ends of the uprights.

A further object of the invention is to provide a swing with opposing seats, each seat including an inclined back rest bolted to the vertical hanging bars which support the seats for swinging motion, and connected to the stationary supports of the lawn swing by self-centering hangers.

With the above and other objects in view the invention relates to certain new and useful constructions, combinations and arrangements of parts, clearly described in the following specification, and fully illustrated in the accompanying drawings, in which:

Fig. 1 is a side elevation.

Fig. 2 is a front elevation, partly broken away.

Fig. 3 is a fragmentary elevation of the mounting for the main shaft or supporting bar.

Fig. 4 is a fragmentary side view thereof, partly in section.

Fig. 5 is a view partly in section and largely in elevation of the hanger for each of the vertical supports for the swing.

Fig. 6 is a fragmentary sectional view, taken on line 6—6 of Fig. 1, looking in the direction of the arrows.

Fig. 7 is an enlarged fragmentary sectional view thereof.

Fig. 8 is a fragmentary side view of the joint between the back rest of the seat and the lower end of the hanger bar for the swing.

Fig. 9 is a fragmentary plan view showing the truss connection between the companion supporting frames.

Referring to the drawings, which illustrate a practical embodiment of the invention, 5 designates one end supporting frame and 6 the companion end supporting frame, each frame being made in duplication of the other. One only will be described in detail.

Each frame consists of upright supporting bars 7 and 8, which are inclined upwardly so their upper ends will be closer together than their lower ends. The lower end portions of the upright bars 7 and 8 are connected to each other by the cross bar 9, and the end portion of this cross

bar 9 is connected to the upright bar 7 by means of the brace 10, and the other end portion of the horizontal tie bar 9 is connected by the brace 11 to the upright bar 8.

5 The upper end of the upright bar 7 is equipped with a metal plate 12, which is attached thereto by bolts 13, and to this plate the end of the hanger shaft or bar 14 is connected, as by the weld 14a. The plate 12 is welded to the end of the hanger bar or shaft 14 in diagonal relation thereto, so that the plate can be secured in the same inclined plane as the upright bar 7, while the shaft 14 is held in an approximately true horizontal plane.

10 The other end of the shaft 14 is welded to the plate 15, which is bolted to the upper end of the upright 8 by means of the bolts 16, and the plate 15 is connected to the shaft 14 in diagonal relation for the purpose explained with reference to plate 12.

15 A hanger shaft 17 is welded at one end to the diagonal plate 12, and at the other end to a similar diagonal plate 19, and these plates are secured by bolts to the upper ends of the frame uprights 7 and 8 of the frame 6. The two hanger shafts 14 and 17 are disposed in approximately the same horizontal plane.

20 On the hanger shaft 14 the upper ends of the hanger bars 20 and 21 are mounted by means of the strap metal U-shaped hangers 20a and 21a, which form loops through which the shaft 14 extends. The lower ends of the hanger bars 20 and 21 are mounted on the lower cross shaft 22. On this shaft the ends of the horizontal platform bars 23 and 24 of the swing platform, which includes the foot slats 25, are mounted for pivotal movement.

25 On the hanger shaft 17 the hanger bars 26 and 27 are supported by the strap hangers, which are U-shaped. Each of these hangers is bolted directly to its hanger bar. The lower ends of the hanger bars 26 and 27 carry the horizontal cross shaft 30, and this cross shaft pivotally supports the platform side bars 23 and 24, so that the platform is held in an approximate horizontal plane.

30 The hanger bars 20 and 21 support the seat back bars 31, the lower ends of which are cut diagonally, as shown in Fig. 8, and secured by the cross bolts 32 to the bars. On the seat back bars 31 back rest slats 33 are mounted, by means of the connecting frame cross bars 34 and 35. The entire seat back rest thus provided is supported in upwardly and outwardly inclined relation to the hanger bars.

35 Side seat supporting bars 36 are bolted to the

hanger bars 20 and 21, and to the back rest bars 31, and are provided with seat slats 37. These bars are constructed with profiles so that the slats will have the required comfortable bearing engagement with the person sitting thereon. Above the side seat bars 36 the tension brace bars 38 connected at their inner ends to the hanger bars 20 and 21, and at their outer ends to the seat back bars 31, hold the seat back rest in fixed angular or inclined relation to the platform and seats. The hanger bars 26 and 27 similarly support the seat 39, and the seat back rest 40.

The upper ends of the hanger bars 20 and 21 are rigidly spaced apart by the bar 41, and the upper ends of the hanger bars 26 and 27 are rigidly spaced apart by means of a similar spacing bar.

The frame 5 is connected to the frame 6 on each side by means of the truss work, comprising the brace bars 42 and 43, which cross each other at 44 and are secured at the points of intersection to each other by the bolt 44a. One end of each brace bar is secured to each upright frame. This truss connection rigidly holds the two upright supporting frames inclined upwardly toward each other, as shown in Fig. 1, thus adding greatly to the stability of the swing and to its satisfactory operation.

The ends of the cross shafts may be equipped with cotter pins 45, and with washers 45a, so that they may be assembled with little mechanical skill, or taken down for storage or shipment. A single bolt connects each U-shaped strap hanger to its hanger bar, so that a slight lateral swinging motion may be permitted.

All of the frame parts of the stationary supports and the swing are constructed with light wood or other suitable material, and the connection between the parts thereof afford great rigidity and strength to the stationary supporting frames, and parallel swinging motion for the two seats.

The improved swing will improve the appearance of any lawn in which it is installed, and can be easily taken apart when the outdoor use of the swing is no longer practical.

Having described the invention, it is understood that various changes in the details of con-

struction, their connection and combination, may be varied in carrying out the invention, as defined by the claims hereof.

Having described the invention, I claim as new:

1. A swing construction, comprising a pair of stationary frames, crosswise disposed brace bars connecting the upper ends of the frames, each frame including upright supporting bars, a hanger shaft disposed between the upper ends of the upright bars of each frame, the extremities of said shaft being formed with faces inclined to the axis of the shaft and diagonal plates welded to the extremities of said hanger shaft and bolted to the upper ends of the upright bars of each frame, hanger bars supported for swinging movement on each hanger shaft, a platform pivotally connecting the lower ends of the hanger bars to each other, and seats and seat back rests carried by each set of hanger bars above said platform.

2. A swing construction, comprising a pair of stationary frames, each frame including upright members disposed in inclined relation to each other, a truss connecting the upper ends of the frames to each other on each side thereof, a cross shaft disposed between the uprights of each frame, the extremities of said shaft being formed with faces inclined to the axis of the shaft and diagonal plates welded to the extremities of the cross shaft and secured to the uprights of the frames, hanger bars suspended on the cross shafts, a platform connected to the lower ends of the hanger bars, seats and seat back rests carried by the hanger bars, and a spacer bar disposed between the upper ends of the hanger bars.

CHARLES J. KLISS.
